US00D524785S

(12) **United States Design Patent** (10) **Patent No.:** **US D524,785 S**
(45) **Date of Patent:** **** Jul. 11, 2006**

(54) **MOBILE-PHONE THERMAL IMAGER**

(75) Inventor: **Li Huang**, No. 26, Shucheng Road, Wuhan, P.R. (CN), 430070

(73) Assignee: **Li Huang**, Wuhan (CN)

(**) Term: **14 Years**

(21) Appl. No.: **29/222,967**

(22) Filed: **Feb. 7, 2005**

(51) LOC (8) Cl. **14-03**

(52) U.S. Cl. **D14/138; D16/208**

(58) **Field of Classification Search** D14/137, D14/138, 147-148, 247-248, 144, 341-347; 379/433.01-433.13, 434; D21/517; 455/575.3, 455/566, 575.1; 345/169; 348/376, 14.02; D16/203, 208

See application file for complete search history.

(57) **CLAIM**

The ornamental design for a mobile-phone thermal imager, as shown and described.

DESCRIPTION

FIG. 1 is a perspective view of the mobile-phone thermal imager of the present invention showing the new design; FIG. 2 is a front view thereof; FIG. 3 is a back view thereof; FIG. 4 is a top plan view thereof; FIG. 5 is a bottom plan view thereof; FIG. 6 is a left side view thereof; FIG. 7 is a right side view thereof; FIG. 8 is a perspective view of the mobile-phone thermal imager of the present invention where the cover is opened; FIG. 9 is a front view of the mobile-phone thermal imager of the present invention where the cover is opened; FIG. 10 is a left side view of the mobile-phone thermal imager of the present invention where the cover is opened; and, FIG. 11 is a right side view of the mobile-phone thermal imager of the present invention where the cover is opened.
